UNITED STATES PATENT OFFICE

2,588,244

CAN-OPENING DEVICE

Elof Johanson, deceased, late of Chicago, Ill., by
Thomas D. Nash, administrator, Chicago, Ill.

Application December 26, 1950, Serial No. 202,750

2 Claims. (Cl. 220—52)

1

The present invention relates generally to can opening devices. More particularly the invention relates to that type of device which is primarily designed as a medium or instrumentality for opening a can of the kind that consists of a cup-shaped body, a skirt equipped cover, and a tongue equipped soldered-in-place tear band between the upper end of the side wall of the body and the lower end of the skirt of the cover, and as its principal parts or components comprises: (1) an elongated supporting member which is adapted in connection with use of the device to be placed in a substantially diametric position on the top wall of the cover and embodies on one end thereof a vertically extending bearing; and (2) a vertically extending shaft which has its central portion journaled in the bearing, embodies a diametric slot in its lower end for receiving the tongue on the tear band of the can, and is adapted when it is turned after insertion of the tongue into the slot to wind the tear band around it and thus effect release of the cover of the can from the can body.

One object of the invention is to provide a can opening device of this type which is an improvement upon, and has certain inherent advantages over, previously devised devices for the same purpose and is characterized by the fact that it is essentially simple in design and construction, embodies a novel arrangement of parts, consists of but three parts and is capable of being produced at an extremely low cost.

Another object of the invention is to provide a can opening device of the aforementioned type in which the elongated supporting member is formed of a single piece of comparatively heavy gauge wire and embodies a pair of spaced apart side pieces, certain adjacent ends of which are connected together by a U-shaped end piece and the other ends of which extend inwards and terminate in two upstanding loose helixes which have the convolutions thereof in interleaved relation and together form the vertically extending bearing for the rotatable shaft.

A further object of the invention is to provide a can opening device of the type and character under consideration in which the upper end of the shaft is bent outwards and then upwards to form a crank for shaft turning purposes and the lower end of the shaft is provided above the diametric tongue receiving slot with a fixed washer which coats with the inner end of the horizontally extending arm part of the crank to retain the shaft against axial or longitudinal displacement with respect to the bearing that con-

2

stitutes a part of the supporting member and is formed by the two aforesaid loose helixes in interleaved relation.

A still further object of the invention is to provide a can opening device which is generally of new and improved construction and effectively and efficiently fulfills and serves its intended purpose.

Other objects of the invention and the various advantages and characteristics of the present can opening device will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a top perspective showing a device embodying the invention in its proper operative position on the top wall of a conventional tear band equipped can and illustrating the manner in which the device serves in connection with turning of its vertically extending shaft to remove the tear band so as to release the cover of the can from the can body;

Figure 2 is a composite view showing in perspective and dismantled relation the three component parts of the device; and

Figure 3 is a vertical longitudinal section illustrating in detail the construction and arrangement of the two loose interleaved helixes which serve to form the bearing for the crank equipped shaft.

The device which is shown in the drawing constitutes the preferred form or embodiment of the invention. It serves as a medium or instrumentality for opening a conventional tear band equipped can and consists of but three parts, namely, an elongated supporting member 5, a rotatable shaft 6 and a washer 7. The can is designated in the drawing by the reference numeral 8 and consists of a cup-shaped body 9, a cover 10, and a tear band 11. The body of the can is formed of sheet metal and consists of a circular bottom wall 12 and a cylindrical side wall 13. The side wall of the body is connected to, and extends upwards from the edge portion of the bottom wall and embodies a short distance beneath its upper edge an outwardly extending continuous bead 14. The cover of the can 8 is formed of sheet metal, consists of a circular top wall 15 and a cylindrical depending skirt 16.

The skirt is connected to the edge portion of the top wall and when the cover is in its closed position fits snugly around the portion of the body side wall that is above the bead 14. The tear band 11 serves releasably to secure the cover in place on the body. It extends completely around the aforementioned portion of the body side wall and the lower portion of the cover skirt and is soldered or otherwise secured in place. One end of the band is provided with an outwardly extending tongue 17 whereby the band may be turned from its normal operative position in order to release the cover so that it may be removed from the body of the can. As described more in detail hereafter the three part device serves when properly operated or manipulated to tear the band 11 by a winding action.

The supporting member 5 of the device is horizontally elongated and is formed of a single piece of comparatively heavy gauge wire. It embodies a pair of side pieces 18 and is adapted in connection with use of the device to be placed in a diametric position on the top wall 15 of the can cover 16, as shown in Figure 1 of the drawing. The side pieces 18 of the supporting member 5 are preferably straight. They are disposed in spaced apart parallel relation and have certain adjacent ends thereof connected together by a U-shaped end piece 19. The last mentioned piece is preferably semi-circular. The other ends of the side pieces 18 are bent inwards and terminate in two upstanding loose helixes 20. As clearly shown in the drawing the convolutions of the two helixes are arranged in interleaved coaxial and abutting relation and form a vertically extending bearing at the ends of the side pieces 18 that are remote from the U-shaped end piece 19. It is contemplated that the convolutions of the two helixes will be formed by twisting or bending the extremities of said other ends of the side pieces around a vertically extending mandrel corresponding in diameter to the shaft 6. If desired the convolutions of the helixes may be soldered together in order that the bearing that is formed by the two helixes is rigid or of unitary character. The uppermost convolution is preferably machined or ground so that the top surface thereof is substantially flat and extends at right angles to the axis of the bearing. In connection with use of the device the wire formed supporting member 5 is positioned with respect to the cover of the can 8 so that the side pieces 18 overlie the top wall of the cover and the helix formed bearing is disposed directly outwards of the annular depending skirt 16.

The shaft 6 extends vertically and has the central portion thereof journalled in the aforementioned helix formed bearing and has at the lower end thereof a diametric slot 21 for receiving the tongue 17 on the outer end of the tear band 11 of the can. The upper end of the shaft 6 is bent outwards at right angles, and then upwards at right angles to form a crank 22 in the form of a horizontally extending crank arm 23 and a vertically extending crank handle 24. The length of the lower end of the shaft 6 is such that when the supporting member 5 is in its operative position on the cover of the can the slot 21 is horizontally aligned with the tear band. In connection with use of the device the supporting member 5 is arranged or positioned as heretofore mentioned. Thereafter the tongue 17 on the outer end of the tear band 11 is manipulated so that it extends through the diametric slot 21 in the lower end of the shaft 6. After insertion of the tongue

through the slot the crank is turned so as to cause the tear band to wind around the lower end of the shaft. It is contemplated that the crank will be turned until the band is turned completely from its operative position in order to effect release of the cover from the body of the can. In connection with turning of the crank the horizontally elongated supporting member 5 swings bodily over the top wall of the cover.

The washer 7 constituting the third part of the device extends around the lower end of the shaft 6 at a point directly above the upper end of the slot 21. It is fixed in place by a so-called press fit and coacts with the inner end of the crank arm 23 to retain the shaft 6 against axial or longitudinal displacement with respect to the upstanding bearing that constitutes a part of the supporting member 5 and is formed by the two loose helixes 20.

The herein described can opening device is essentially simple in design and may be fabricated at an extremely low cost due to the fact that it consists of but three parts and the bearing equipped supporting member is formed of a single piece or length of wire. It may be manipulated with facility and effectively and efficiently fulfills its intended purpose.

The invention is not to be understood as restricted to the details set forth since these may be modified within the scope of the appended claims without departing from the spirit and scope of the invention.

Having thus described the invention what is claimed as new and desired to secure by Letters Patent is:

1. As a new article of manufacture, a device adapted to open a can of the type that consists of a cup-shaped body, a skirt equipped cover and a tongue equipped removable tear band between the upper end of the side wall of the body and the lower end of the skirt of the cover, and comprising a horizontally elongated supporting member adapted in connection with use of the device to be placed in a substantially diametric position across the top wall of the cover of the can, formed of a single length of wire, and embodying a pair of spaced apart side pieces having certain adjacent ends thereof connected together by a U-shaped end piece and their other ends bent inwards and terminating in two upstanding loose helixes which have the convolutions thereof in interleaved and coaxial relation and together form a vertically extending bearing that is adapted when the supporting member is in place to assume a position wherein it is directly above and outwards of the skirt of the cover, and a vertically extending shaft having the central portion thereof journalled in the bearing, embodying in its lower end a diametric slot for receiving the tongue of the tear band of the can, having the upper end thereof provided with turning means, and adapted when it is turned by said means after insertion of the tongue into the slot to wind the tear band around its lower end and thus effect release of the cover of the can from the can body.

2. As a new article of manufacture, a device adapted to open a can of the type that consists of a cup-shaped body, a skirt equipped cover and a tongue equipped removable tear band between the upper end of the side wall of the body and the lower end of the skirt of the cover, and comprising a horizontally elongated supporting member adapted in connection with use of the

device to be placed in a substantially diametric position across the top wall of the cover of the can, formed of a single length of wire, and embodying a pair of spaced apart side pieces having certain adjacent ends thereof connected together by a U-shaped end piece and their other ends bent inwards and terminating in two upstanding loose helixes which have the convolutions thereof in interleaved coaxial and abutting relation and together form a vertically extending bearing that is adapted when the supporting member is in place to assume a position wherein it is directly above and outwards of the skirt of the cover, a vertically extending shaft having the central portion thereof journaled in the bearing, embodying in its lower end a diametric slot for receiving the tongue of the tear band of the can, having the upper end thereof bent outwards and then upwards to form an integral crank for shaft turning purposes, and adapted when it is turned by manipulation of the crank after insertion of the tongue into the slot to wind the tear band around its lower end and thus effect release of the cover of the can from the can body, and a washer mounted fixedly 25

on the lower end of the shaft at a point above the slot and positioned so that it engages the lower end of the bearing and coacts with the inner portion of the crank to retain the shaft against axial displacement in either direction relatively to said bearing.

THOMAS D. NASH,
*Administrator of the Estate of Elof Johanson,
Deceased.*
